GYRATORY CRUSHER

Jasper A. McCaskell, Glenwood, N. Mex., assignor
to William M. McCaskell, Glenwood, N. Mex.

Application April 16, 1935, Serial No. 16,538

15 Claims. (Cl. 83—10)

This invention relates to improvements in gyratory crushers and is more particularly a development of the apparatus shown in my prior Patent No. 1,936,728, issued on November 28, 1933.

5 The principal object of my present invention is to provide a linkage for operating the muller shaft of a gyratory crusher so that under normal conditions the muller will exert a more nearly positive crushing force on materials handled, and
10 when an obstruction is encountered, the muller will tend to crush the obstacle and then after an interval, if crushing is too difficult, the linkage will move the muller more quickly to a concentric, non-crushing position, thereby being more positive in crushing and more sensitive in subsequent reaction than was possible heretofore.

Another object of my invention is to provide an improved drive for a gyratory crusher having a weighted eccentric intermediate a crank arm and the muller shaft with the center of gravity of the eccentric so placed that centrifugal forces will tend to hold the muller in crushing position, but which will tend to move the muller shaft toward a concentric position on a short radius so that, if an obstacle is encountered which the crusher is unable to crush, the non-crushing position is reached more quickly.

A further object of my invention is to increase the crushing efficiency of a muller shaft eccentric drive mechanism for a gyratory crusher by maintaining a ratio between the length of the crank arm and the distance between the crank pin center and the center of gravity of the operating eccentric which is three or more, while providing 35 for concentric return of the muller shaft to coincidence with the drive shaft for non-crushing relation.

Another and more specific object of my invention is to provide a plurality of eccentrics coaxial in a crank pin socket with the end of a muller shaft of a gyratory crusher, such eccentrics having a combined eccentricity such that the muller shaft can be made concentric with the crank socket, while one of the eccentrics is so weighted 45 that it has its center of gravity at a point less than one third as far from the center of the crank pin socket as is the center of the crank pin socket drive member.

Another specific object of my invention is to 50 provide a single weighted eccentric for a muller shaft drive in which the center of gravity is approximately one third as far from the crank pin socket as is the center of the drive of the crank pin socket so that the center of gravity tends to move on a short arc as compared to the

eccentric center thereby making the eccentric more sensitive under abnormal operating conditions and more positive under normal operating conditions.

Another object of my invention is to provide 5 an improved adjustment of the elevation of the muller shaft with respect to the crusher jaws such that the fineness of grind may be controlled during operation of the machine.

Other objects and advantages of my invention 10 will appear from the following description thereof, taken in connection with the drawings which illustrate preferred forms of embodiment of my invention and in which,

Figure 1 is a central vertical sectional view of 15 the crusher embodying my invention.

Fig. 2 is a horizontal section taken substantially along the line 2—2 of Fig. 1.

Fig. 3 is a partial vertical section taken substantially along the line 3—3 of Fig. 2. 20

Fig. 4 is a horizontal section taken substantially along the line 4—4 of Fig. 3 and showing the normal operating position of the respective elements.

Fig. 5 is a detailed vertical section showing 25 the releasing pin structure.

Fig. 6 is a horizontal section substantially like Fig. 2 but showing the counterweight of the operating eccentric moved into advanced position.

Fig. 7 is a partial vertical section taken along the line 7—7 of Fig. 6 and showing the locking 30 pin locking the eccentrics together.

Fig. 8 is a horizontal section substantially like Fig. 4 showing the muller shaft concentric with the drive shaft.

Figs. 9 and 10 are diagrammatic illustrations 35 of the angular relation of the centers of the respective elements.

Fig. 11 is a horizontal section showing a muller 40 drive having one eccentric with the eccentric in operating conditions, and

Fig. 12 is a horizontal section similar to Fig. 11 but showing the eccentric in collapsed, or concentric position.

In my prior patent, I disclosed a gyratory type crusher for crushing and pulverizing ore and 45 other refractory material in which the muller shaft was driven by a motor through a centrifugally controlled eccentric so that when an oversized or overhard piece of material became lodged between the muller and the crushing 50 jaws, the centrifugally controlled eccentric would move the muller shaft center to a new or concentric position thus increasing the distance between the muller and the crushing jaws and in turn freeing the muller shaft for continued op- 55

eration. The eccentric therefore established a concentric muller shaft center under adverse conditions and after the release of the material, the eccentric was subsequently returned to normal operating position by any suitable means.

I now find that in order to get better operating results, a suitable ratio between the length of the crank arm and the distance of the center of gravity of the eccentric from the center of the 10 crank pin should be maintained. The greater this proportion is under practical operating conditions the more efficient this couple becomes. There is a certain physical relation however, between the center of gravity and the eccentricity 15 of the eccentric due to manufacturing conditions and I find it desirable to keep the eccentricity as small as possible in order to maintain a maximum ratio between the length of the crank arm and the distance between the crank 20 pin center and the center of gravity of the eccentric. But in order to make the muller shaft and the drive shaft concentric after the eccentric revolves 180°, it is necessary that the eccentricity of the eccentric equal the length of the 25 crank arm and this would normally eliminate any increase in ratio between these two lengths thus tending to inefficiency in the operation of this couple.

In my preferred construction, I now provide an 30 additional or auxiliary eccentric which establishes a new crank pin center as far as the operating eccentric is concerned and the operating eccentric can have an eccentricity substantially less than the length of the crank arm for the desired high ratio, while the total eccentricity of 35 the two eccentrics equals the length of the crank arm for the desired concentric relation of the muller shaft.

In order to more clearly illustrate the preferred structure I have shown a complete gyratory crusher in Fig. 1 which is mounted on a base 8 of a suitable type which may have the driving motor 10 mounted on the top. The motor 10 drives the drive shaft 12 through a suitable 40 coupling 14 and on the end of the drive shaft and keyed thereto is the crank socket 16 carried in anti-friction relation on the foot bearing 17 by the bearings 19. The crank socket 16 carries an auxiliary eccentric 18 and inside of the auxiliary eccentric 18 is the operating eccentric 20.

The details of the drive end of the drive shaft are shown in Fig. 3 in which it will be seen that the operating eccentric 20 is provided with a counterweight 22 which extends substantially 45 entirely around its periphery as shown in Fig. 2. The operating eccentric is preferably provided with a bearing liner 23 which in turn carries the muller drive bearing 24 in the end of which is supported the muller shaft 30 as by a partial 50 spherical bearing 25. The bearing 25 and the liner 23 each facilitate the movement of the muller shaft which is both rotative and oscillatory.

The muller jaws 32 are mounted part way up 65 the muller shaft 30 in a fixed position as shown in Fig. 1, and at a point spaced adjacent the muller jaws 32 are the fixed crusher jaws 34, such jaws being spaced below the hopper 36 to receive the ore to be crushed. The upper end 70 of the muller shaft 30 is carried on a suitable spherical shaped bearing 38 which will be described hereinafter.

The materials to be crushed which are placed in the hopper 36 will pass between the crushing 75 jaws 34 and the muller 32 and being crushed

and pulverized, will drop to the discharge openings 42 in the base 8 as desired. As the finely ground material is objectionable in the bearings the foot bearing 17 and other movable parts are covered by a suitable housing 43 which as shown, 5 will prevent the parts from becoming clogged.

The detailed construction of the preferred form of eccentrics is shown in Figs. 2 to 8 inclusive. Under normal operating conditions, the auxiliary eccentric 18 is locked to the crank 10 socket 16 to rotate therewith. This is accomplished by a locking pin 44 normally held in locking position as shown in Fig. 3. Preferably the median line of the auxiliary eccentric is in advance of the dead center line through the 15 center of the drive shaft socket and the center of gravity of the eccentric in the direction of the rotation of the crusher from 15° to 25° or sufficient to make the eccentric have a tendency to tighten against a stop in crank socket 16. This 20 removes the strain from the locking pin when the crusher is operated normally. It will of course be understood that a similar result would be had if the eccentric were so constructed that its median line lags behind the dead center line 25 from 15° to 25°.

The operating eccentric 20 although free to move in the socket of the auxiliary eccentric, is normally held in eccentric relation by centrifugal force, as the crank socket is rotated in the 30 order of 1800 R. P. M. and the muller shaft is then held firmly in crushing position. If an obstacle is engaged however, the operating eccentric will travel a distance equivalent to approximately 45° in advance of the auxiliary eccentric 35 and at that point the casing of the counterweight 22 contacts with the release bar 46 shown in Fig. 5.

Engagement of the bar 46 causes movement of the lever 48 to withdraw the locking pin 44 from the crank socket and force it into a suitable recess 20a in the operating eccentric 20. This will thus relieve both eccentrics from the crank socket 16 and in turn will lock the two eccentrics together. Both eccentrics will then swing 45 together until the operating eccentric 20 has traveled approximately an additional 135° or until the muller shaft 30 has become concentric with the drive shaft 12 and then the lock 49 on the crank socket engages a suitable recess 18a on the auxiliary socket so that all operating parts 50 are locked together in a concentric non-crushing position of the muller shaft as shown in Fig. 8.

A diagrammatic representation of this action of the eccentric is illustrated in Figs. 9 and 10. 55 If the point A is considered the center of the drive shaft and point B to be the equivalent position of a crank pin center, the length of crank arm is A B. If it also be assumed that equivalent length links are used rather than the internal 60 eccentric sockets, the length B E is equivalent to the eccentricity of the auxiliary eccentric and the length E C is equivalent to the eccentricity of the operating eccentric. Under normal operation, the muller shaft, having its center at C will 65 be driven around the drive shaft A as its center with the effective crank arm A B E due to the positive lock 44 between A B and B E, and the floating eccentric length E C. The point E under these conditions is a free pivot for movements of 70 the operating eccentric up to 45°.

Under the abnormal conditions before mentioned, the operating eccentric E C can move approximately 45°, about E as a center. At this point, the unlocking of lock 44 and locking of the 75

two eccentrics will cause a combined movement about B as a new center until the muller shaft (point C) has reached the drive shaft center (point A) and is concentric therewith.

- 5 The center of gravity of the counterweight 22 is placed in such a position that the maximum efficiency of the apparatus can be had. It is of course to be considered that manufacturing conditions make it necessary to limit its position
 10 within a certain range but I find it desirable to place it by mathematical computation with reference to the effective crank arm length which in this case is the combined distance of the crank arm length and the length of the locked eccentric.
 15 A ratio, of 3 or more between the effective crank arm (A B E) and the distance of the center of gravity from the effective crank pin center E has been found to be especially suitable as it brings about a normally strong centrifugal force
 20 for crushing and yet the operating radius, on the diagram, E C is so small that rapid results are obtained. With a concentric weight the center of gravity of the operating eccentric would be at C although with a horseshoe shape weight as
 25 shown, the center of gravity of the operating eccentric is at a point slightly beyond the center of the operating eccentric from the crank pin.

In the diagram, both eccentrics are shown to have substantially equal eccentricities but this
 30 is not necessary. The shorter the link of the operating eccentric the shorter radius its center of gravity will tend to move on in case of abnormal operation and therefore the quicker the eccentrics will move into collapsed position. The
 35 only limitation as to size is a practical one although the combined eccentricity of the two eccentrics preferably provides for movement of the muller shaft to a concentric position with the drive shaft.

40 It will be seen that with a structure, there is a maximum ratio between the length of the crank arm and the distance between the center of gravity of the eccentric and the center of the crank pin. The efficiency of operation thereby becomes
 45 a maximum.

The operating eccentric 20 may be constructed so that its median line is in line with the center of gravity line through the center of the crank socket, or it may be in advance of or lag behind
 50 this center line. By the preferred construction, the median line of the operating eccentric lags behind the center of gravity line approximately 50°, see Fig. 2.

Under normal operating conditions, the muller
 55 shaft 30 carries the muller in crushing relation to the crusher jaws. This is a position of very little clearance with the result that a hard and uncrushable particle will react on the respective eccentrics in such a manner that the muller shaft

60 may be made concentric with the drive shaft as shown in Fig. 8. After the obstruction in the crusher has been removed the locking member 49 can be released by projecting a suitable tool through the casing 43 or mechanical means can
 65 be used to contact with the outer bearing socket to release the pin and the eccentrics will then swing to their normal operating position.

The fineness of grind of the muller can be conveniently changed by raising the muller shaft
 70 30 and the muller 32, such as by means of a worm 50 shown in Fig. 1. The worm is operated by a suitable crank 51 or by any other desired means and in turn will rotate the worm gear 52 which is keyed to the lower half of the bearing 38. This
 75 in turn is provided with a screw thread and in

rotation will force the entire bearing 38 in a vertical manner to control the proximity of the muller 32 to the crusher jaws 34.

This adjustment can be made when the crusher is running to obtain the desired fineness without the necessity of closing down the crusher as was formerly necessary. Furthermore, as the crushing surfaces wear, a slight turn of the worm will maintain the same relative position of the crushing surfaces for the delivery of a uniform product at all times. This brings about a great saving in time as under former constructions it was only possible to adjust the muller under non-operating conditions and it was necessary to repeatedly experiment with the changed position for the proper set of the crushing surfaces.

I also preferably provide a full pressure lubricating system for the reduction of bearing wear. The lower part of the casing 43 has a sump 55 for oil which returns to the cooler 56 through the intake pipe 57. Oil is also drawn from the roller bearings 19 through the pipe 58 and from the upper bearing 38 through pipe 59. After being suitably cooled in the cooler 56, it is pumped from the pump 60 initially into the chamber 61 from which point part of the lubricant flows through the muller shaft 30 into the lower bearing and the other part lubricates the upper bearing as needed. The pump may be driven by any suitable means (not shown.)

A modified form of construction of eccentric is diagrammatically shown in Figs. 11 and 12 in which a single eccentric 65 is mounted on the crank pin 66 of the crank 67. In this construction, the eccentric is provided with counterweights 68 35 with the center of gravity line passing the axis approximately at the point 69. It will be seen that by suitable counterweights this center of gravity can be placed at such a point so that its distance from the crank pin 66 is a fraction of the 40 length of the crank arm. This ratio of crank arm length to effective operating radius of the center of gravity can be three or more as in the previous case with similar beneficial results.

The drawings are intended to illustrate the 45 principle of drive linkage which is effective in giving adequate crushing power and yet permit the operation of the floating eccentric when an uncrushable particle is encountered. The precise details of size and parts however, depends on the 50 type of crushing and materials crushed. Other modifications can also be made in arrangement of parts and the invention is therefore not to be considered as limited to any particular size or shape of parts but is to be given a broad interpretation within the scope and spirit of the description herein and of the claims appended hereinafter.

I claim:

1. A gyratory crusher of the class described 60 having a fixed crusher jaw and a gyratory muller corresponding therewith, a muller shaft carrying said muller and means to rotate one end of the muller shaft, including a crank, a floating eccentric carried by the crank pin of said crank and 65 a bearing for said muller shaft on said eccentric, said eccentric having a center of gravity at such a distance from the crank pin center that the radius of rotation of the eccentric about the crank pin center is substantially smaller than the length 70 of the crank, said eccentric being adapted to move the muller shaft center into substantial coincidence with the crank center if an obstruction is encountered at the crusher jaws.

2. A drive linkage for rotating a muller shaft 75

about a crank center for gyrating motion of a muller carried on said shaft which comprises a crank mechanism having an effective crank pin center, a floating eccentric carried at the effective crank pin center, said eccentric having a bearing for one end of the muller shaft, a weight on said floating eccentric, the centrifugal force of which tends to maintain the radius of rotation of said muller shaft, the center of gravity 10 of said weight being so placed with respect to the crank pin center that it has a radius of rotation about said effective crank pin center if an obstacle is encountered that is short as compared to the effective crank arm length, said eccentric 15 being adapted to move the muller shaft into a concentric position with the crank center.

3. A gyratory crusher having a casing, a crusher jaw, a muller shaft with a muller adjacent said jaw, and means to gyrate one end of said muller shaft, said means including a crank socket, an auxiliary eccentric and an operating eccentric actuated by said crank socket, said auxiliary eccentric and crank socket forming an effective crank arm with an effective crank pin center, 20 said operating eccentric having a counterweight with a center of gravity at a distance from the effective crank pin center which is relatively small as compared to the length of the effective crank arm, whereby the initial movement of the operating 25 eccentric will be on a short arc.

4. A gyratory crusher of the class described having a fixed crusher jaw and a gyratory muller cooperating therewith, a muller shaft carrying said muller and means to rotate one end of the 30 muller shaft, including a crank, a floating eccentric carried by the crank pin of said crank and a bearing for said muller shaft on said eccentric, said eccentric having a center of gravity at such a distance from the crank pin center that the 35 radius of rotation of said center of gravity about the crank pin center is of the order of one third the length of the crank, said eccentric being adapted to move the muller shaft center into substantial coincidence with the crank center if 40 an obstruction is encountered at the crusher jaws.

5. A gyratory crusher having a casing, a crusher jaw, a muller shaft with a muller adjacent said jaw, and means to gyrate one end of said muller shaft, said means including a crank socket, an auxiliary eccentric and an operating eccentric, said auxiliary eccentric being actuated by said crank socket and actuating said operating eccentric, said operating eccentric carrying the 55 end of the muller shaft, means to normally lock said auxiliary eccentric in eccentric relation to said crank socket to form an enlarged effective crank arm and means to lock said operating eccentric to said auxiliary eccentric and to unlock said auxiliary eccentric from said crank socket when said operating eccentric is moved through a pre-determined angle.

6. A gyratory crusher of the class described having a fixed crusher jaw and a gyratory muller 60 cooperating therewith, a muller shaft carrying said muller and means to rotate one end of the muller shaft, including a crank, a floating eccentric carried by the crank pin of said crank and a bearing for said muller shaft on said eccentric, 65 said eccentric having a center of gravity at such a distance from the crank pin center that its radius of rotation about the crank pin center is substantially smaller than the length of the crank, said eccentric being adapted to move the 70 muller shaft center into substantial coincidence

with the crank center if an obstruction is encountered at the crusher jaws, and means to lock the eccentric in concentric position.

7. In a gyratory crusher, a crusher member, a muller shaft having a muller adjacent said crushing member, and means to gyrate said muller in crushing relation with said crusher member, said means including a driven crank and a plurality of eccentrics, one of said eccentrics having a bearing for one end of said muller shaft, locking means to normally lock the crank and one eccentric together and means carried by the other eccentric to unlock the eccentric and crank and to lock the two eccentrics together when an obstacle is engaged at the crusher member, the eccentricity of the locked eccentrics being such that the gyrating end of the muller shaft will move to a position concentric with the other end. 10

8. A gyratory crusher of the class described having a fixed crusher jaw and a gyratory muller 20 cooperating therewith, a muller shaft carrying said muller and means to rotate one end of the muller shaft, including a crank, a floating eccentric carried by the crank pin of said crank and a bearing for the gyratory end of said muller 25 shaft on said eccentric, said eccentric having a center of gravity at such a distance from the crank pin center that the radius of rotation of the center of gravity about the crank pin center is substantially smaller than the length of the 30 crank, said eccentric being adapted to move the muller shaft center into substantial coincidence with the crank center if an obstruction is encountered at the crusher jaws, said eccentric having a center of gravity on a line through the 35 center which is at a leading angle with respect to a median line through the center of the crank pin and the center of the eccentric.

9. A gyratory crusher of the class described having a fixed crusher jaw and a gyratory muller 40 cooperating therewith, a muller shaft carrying said muller and means to rotate one end of the muller shaft, including a crank, a floating eccentric carried by the crank pin of said crank and a bearing for said muller shaft on said eccentric, 45 said eccentric having a center of gravity at a distance from the crank pin center such that the radius of rotation of the center of gravity about the crank pin center is of the order of one third the length of the crank or less, the center of 50 gravity of said eccentric being on a line through the center which is at a leading angle with respect to a median line, said eccentric being adapted to move the muller shaft center into substantial coincidence with the crank center if 55 an obstruction is encountered at the crusher jaw, and means to lock the eccentric in concentric position.

10. In a crusher having a stationary crusher member and a movable crusher member 60 cooperating therewith, means for moving the movable crusher member to and from the stationary crusher member including a crank having a crank pin and a floating eccentric, said floating eccentric being freely rotatable about said crank pin, 65 said floating eccentric having a counterweight so positioned with respect to the crank pin that the length of the crank is at least three times the distance of the center of gravity of the eccentric from the crank pin. 70

11. In a gyratory crusher having a casing, a muller shaft having a muller thereon, said casing having crusher jaws adjacent said muller, a relatively fixed point bearing for one end of said muller shaft, and a crank for gyrating the 75

- other end of said muller shaft, means to move said muller shaft to a concentric position, means to hold said muller shaft in said concentric position and means to move said muller shaft with 5 respect to said crusher jaws to vary the fineness of grind, said movable means including an adjustable bearing for the relatively fixed point bearing and means to adjust it during operation of the muller.
- 10 12. In a gyratory crusher having a casing, a muller shaft having a muller thereon, said casing having crusher jaws adjacent said muller, an upper semi-spherical shaped bearing for said muller shaft, and a lower crank pin socket for 15 gyrating said muller shaft, means to move said muller shaft to a concentric position on contact with an uncrushable substance and means to hold said muller shaft in said concentric position until said uncrushable substance is removed.
- 15 13. In a gyratory crusher having a casing, a muller shaft having a muller thereon, said casing having crusher jaws adjacent said muller, an upper semi-spherical shaped bearing for said 20 muller shaft, and a lower crank pin socket for gyrating said muller shaft, centrifugal means to move said muller shaft to a concentric position on contact with an uncrushable substance and a releasable linkage to hold said muller shaft in 25 said concentric position, said linkage being manually releasable after the uncrushable substance is removed so that the muller shaft may regain its eccentric position.
- 30 14. In a gyratory crusher having a casing, a muller shaft having a muller thereon, said casing having crusher jaws adjacent said muller, an upper semi-spherical shaped bearing for said muller shaft, and a lower crank pin socket for gyrating said muller shaft, means to move said muller shaft to a concentric position, means to positively hold said muller shaft in concentric position if it moves to such position and means to lubricate said upper bearing and said lower socket and said muller shaft means, said lubricating means including a pressure oil pump and a cooling device.
- 15 16. A gyratory crusher of the class described, having a fixed crusher jaw and a gyratory muller cooperating therewith, a muller shaft carrying 15 said muller and means to rotate one end of the muller shaft, said means including a crank, an auxiliary eccentric mounted on said crank and forming an effective crank arm, a floating eccentric mounted at the end of the effective crank 20 arm, and having a bearing for the end of the muller shaft, said floating eccentric having a counterweight, the center of gravity of the floating eccentric being spaced from the end of the effective crank arm a distance which is relatively 25 short when compared to the length of the effective crank arm so that the floating eccentric will move on a short radius if an uncrushable obstacle is encountered in the crushing jaws, said floating eccentric being adapted to carry the 30 muller shaft into a position substantially concentric with the crank for non-crushing operation.

JASPER A. McCASKELL.
